GEORGE CASSADY, OF NEW WESTMINSTER, BRITISH COLUMBIA,
CANADA.

WEIGHING-MACHINE.

No. 857,870.

Specification of Letters Patent.

Patented June 25, 1907.

Application filed February 11, 1907. Serial No. 356,825.

To all whom it may concern:

Be it known that I, GEORGE CASSADY, a citizen of the Dominion of Canada, residing at New Westminster, in the Province of British Columbia, Canada, have invented a new and useful Improvement in Weighing-Machines, of which the following is a specification.

This invention relates to a weight sorting machine designed to select from a continuous succession of cans delivered to it all that are under a certain predetermined weight, and that will deliver the full weight cans into a chute for delivery from the machine and the light weight ones onto a separate table for subsequent attention.

The machine is fully described in the following specification reference being made to the drawings by which it is accompanied, in which:

Figure 1 is a sectional elevation of the machine on the line A A in Fig. 2, Fig. 2, a plan of the machine, Fig. 3, a section on the line B B in the direction of the arrow B and, Figs. 4 and 5 detail views of the can by which the downward tendency of the scale platform is confirmed and made definite.

The table 4 of the machine is supported at a convenient height from the floor on side frames 2, and the cans are delivered to it by an entering chute 5 in which a feeding and spacing device of approved design may be placed. Forming a continuation of the chute 5 an endless conveyer band 19 passes over the table 4 of the machine in the direction of the arrow F and over band pulleys 18 secured to the driving shaft 16 and a shaft 17 rotatable in bearings in the side frames 2. Beyond where the band 19 passes beneath the table a downwardly inclined delivery chute 6 conveys from the machine the full weight cans, selected in a manner to be described.

Alongside and parallel to the band 19 are slideways 7 on the top of the table 4 which slideways are separated from the band 19 by upwardly projecting strips 11 terminating toward the entering end of the machine at the scale platforms 21. These scale platforms are situated one upon each side of the conveyer band 19 and move in apertures through the table 4. They are of such form in plan, see Fig. 2, that cans C may be swept from their path along the line of the chute 5

and conveyer band 19 onto either platform 21 alternately and each can will rest upon its platform for a sufficient time to determine whether it is of such weight as to depress the platform below the level of the slideways 7 which stand slightly above the level of the upper surface of the conveyer band 19, see Fig. 3, and if the platform falls below the level of the slideway to that of the conveyer band the lower edge of the can will contact with the edge of the aperture through which the platform passes and be directed onto the conveyer band.

Each scale platform 21, see Fig. 1, has a downwardly projecting stem 22 from which toward the upper end laterally project trunnions 33 having V shaped undersides which rest in depressions in the forked ends 34 of a lever 35 fulcrumed at 36 in a standard 37 secured to the cross frame 3 of the machine. The lever 35 is extended beyond the fulcrum 36 and is provided with an adjustable counterweight 38. The free end of the lever 35 normally rests, see Figs. 4 and 5, under the influence of the counterweight 38 upon the hub 66 of a cam flange 65 secured to the driving shaft 16.

The platform 21 is maintained approximately horizontal, and parallel under movement, see Fig. 1, by a lever 42 pivotally mounted by a pin 43 to an attachment on the frame of the machine, which lever is connected at 41 to the lower end of the stem 22, and a counterweight 44 is threaded on the free end of the lever 42 for fine adjustments.

The free end of the lever 35 where it rests upon the hub 66 of the cam flange is provided, see Figs. 4 and 5, with a laterally projecting member 39 having a knife edge opposed to the direction of rotation, and projecting from the flange 65 are cam members 67. These members 67, two in number on each flange, are so situated as to be clear of the member 39 when the lever end is in its normal position resting on the hub 66, in which position the scale platform 21 is level with the plane of the slideway 7 as shown by dot and dash lines in Fig. 1 but if the weight of a can is in excess of the counterweight 38 the platform is depressed and the end of the lever 35 is lifted off the hub 66 and the underside of the member 39 will engage the outer curve of the cam 67 which will lift the lever 35 to complete the depression of the platform to the

level of the upper face of the conveyer band 19 and will retain it there a sufficient time to permit the can which depressed the scale platform to be moved from off it onto the band by the engagement of the lower edge of the can with the curved edge of the aperture in the table occupied by the scale platform. The outer surface of the cam member 67 thereafter curves toward the hub to permit the lever end to fall again on it, which downward movement is rendered positive by a guide member 68 laterally projecting from the cam flange 65 which guide engages the upper side of the laterally projecting member 39 of the lever.

The cans are transferred from their path along the entering chute 5 and conveyer band 19 onto either scale platform 21 by a transfer lever 46 secured on a vertical shaft 47 mounted in a frame 48 which spans the width of the machine adjacent to the scale platform. This traverse lever is oscillated from side to side by any suitable mechanism connected with the driving shaft of the machine. In the drawing the shaft 47 of the transfer lever is shown as operated by a lever 49 secured to its upper end and having an upwardly projecting pin 50, which is connected by a rod 51 to a crank pin 52 secured in a crank disk 53, the disk being secured on a vertical shaft 54 running in bearings in a support 55. The shaft 54 is operated by bevel gears 56 from a shaft 57 driven by a chain 59 passing over sprocket wheels 58 on the shaft 57 and on the driving shaft 16 of the machine.

The cans C are carried off the scale platform 21 and along the slideways 7, or, if the scale platform has been depressed, are diverted onto the conveyer band 19, by fingers 63 laterally projecting from sprocket chains 61 running along the outer edge of each slideway 7 and passing round sprocket wheels 62 secured to the driving shafts 16 and to the shaft 17. At the entering end the fingers of these chains pass over the end of the table 4 or through an aperture therein which is outside of the curved border 13 but at the further end where the fingers have to pass through the slideway 7 a section 8 of that slideway is hinged at 9 to lift upward and permit each finger to pass, the hinged section being operated by a member 10 laterally beyond the width of the slide toward the sprocket chain and upwardly directed that it will be engaged by each finger 5 and lifted as such approaches the hinged section 8.

That portion 14 of the can path adjacent to the scale platform 21 is inclined slightly upward from the level of the top of the conveyer band 19 to the higher level of the slideway 7, with which the upper surface of the scale platform is normally coincident, and this incline is radial so that a portion of it may be on the forward inner corner 15 of the scale platform itself. The particular manner

by which this change of level is attained is however of little importance so long as the cans may be moved off the conveyer band 19 onto the scale platform at one end and off the scale platform onto the slideway 7 when light, or off the platform onto the conveyer band 19 when of full weight.

The driving shaft 16 of the machine is operated by a band pulley 20 secured on it, and from the shaft 16 all the moving parts of the machine are operated, the mechanism being so arranged that the cam control of the balance lever 35 is exercised twice during one revolution of the shaft and similarly the transfer lever 46 carries a can twice to each side during the same movement. This however forms no material part of the invention.

In the operation of the machine the cans are delivered along the entering chute 5 where they may be spaced and successively fed to the weighing machine by a suitable spacing and feeding device. As they come within the reach of the traverse lever 46 they are swept alternately onto one or the other of the scale platforms 21 where they rest for a sufficient time to determine whether or not they are of the required weight. If light the scale platform 21 is not depressed and is later prevented from being depressed, and the can is carried by the fingers 63 of the sprocket chain 61 along the slideway 7 and delivered onto a table for subsequent treatment. If however the weight of the can is sufficient to depress the platform a trifling amount the free end of the lever 35 will be raised to a sufficient extent to bring the knife edge of the member 39 laterally projecting from the lever 35 above the corresponding edge on the projecting cam member 67, the platform 21 will be positively depressed to the limit necessary to bring its level to that of the band 19. In this position as a can is carried along by a finger 63 it will engage the curved edge of the aperture in the table 4 through which the platform passes and will be diverted from the line of the slideway 7 onto the traveling band 19 and will be carried by it to the delivery chute 6 the incline of which will permit them to slide down clear of one another.

Where the machine forms a part of an extended system, the traveling band 19 may extend beyond the limit of the weighing machine and deliver the cans to the next machine in order, such as a can "topper", and similarly the cans may be delivered to the weighing machine by a conveyer band from a can filling machine.

It will be noticed that the operation of the machine is practically continuous as fast as the cans can be fed to it; that the weighing devices are normally at rest; and that the cans only rest on the weighing platform for the brief period necessary to determine if they have any tendency to depress it the sub-

sequent movement of the platform being positively completed mechanically, which latter feature permits of very rapid operation.

5 Having now particularly described my invention and the manner of its operation and use I hereby declare that what I claim as new and desire to be protected in by Letters Patent, is:

10 1. In a weight sorting machine, a scale balance, means for maintaining said scale balance in a relatively fixed position, said scale balance having a platform normally at rest at a definite level, means for conveying articles to said platform, means for mechanically and positively depressing the platform to a definite lower level when a weight is deposited on the platform to depress it slightly below its normal level, means for moving the 15 weight off the platform and directing it in predetermined channels, substantially as shown and described.

2. In a weight sorting machine, the combination with a table suitably supported and having tracks at different levels, a scale balance having a platform arranged adjacent to both tracks, and normally at the level of the higher track, means for moving an article onto the platform of the balance, means for 25 mechanically and positively preventing or confirming any downward movement of the platform to the lower level, means for moving an article off the scale platform and along the high level track if the weight of the article is 30 insufficient to depress the platform of the

balance, and means for directing the article off the scale platform onto the low level track if the weight of such article is sufficient to depress the weight of the balance, and means for conveying the full weight articles 40 along the low level track.

3. In a weight sorting machine, the combination with a table suitably supported having parallel tracks at different levels, a scale balance the platform of which is adjacent to both tracks and moves through an aperture in the table the edge of the aperture through which the platform passes being laterally inclined from the high level toward the low level track, means for mechanically and positively preventing or confirming any downward movement of the platform to the lower level, means for moving an article onto the scale platform, means for conveying an article from the scale platform along the high 50 level track if the weight of such article is unable to depress the platform but that will move the article against the inclined edge of the aperture through which the scale platform passes and deliver it onto the low level 55 track if the weight of the article is sufficient to depress the platform, and means for conveying the article along the low level track.

In testimony whereof I have signed my name to this specification in the presence of 60 two subscribing witnesses.

GEORGE CASSADY.
